HOLE PLUG FOR OIL AND GAS WELLS

George W. Moore, Long Beach, Calif.

Application October 24, 1939, Serial No. 300,979

2 Claims. (Cl. 166—13)

This invention relates to a hole plug for oil and gas wells, and particularly the type of plugs known as bottom hole, bridging, or heaving plugs.

An object of my invention is to provide a novel hole plug of the safety or signaling type, whereby the recovery of unusual or easily distinguishable material from the plug by a bailer or other clean-out tool will indicate to the operator that the well has been cleaned, and that further use of the clean-out tools might cause serious injury to the bottom of the well.

A further object of my invention is to provide a novel hole plug for oil and gas wells, which is formed of a frangible and easily distinguishable material, so that striking of a cleanout tool against the plug will release particles of the plug material, these particles being drawn into the clean-out tools, will indicate to the operator that the well has been cleaned to bottom.

A further object is to provide a novel hole plug of the character stated, with a novel releasable or disengageable support, so that the plug may be left in the hole at the desired point.

Still another object is to provide a novel hole plug of the character stated, with novel means of engaging the wall or casing of the well so that the plug may be positioned at any point in the well above bottom, if desired.

Still another object is to provide a novel hole plug of the heaving or bridging type, in which frangible or recoverable material is enclosed in a housing or casing, and with means provided engageable with the well casing to hold the plug fixedly at any point desired in the well.

Other objects, advantages and features of invention may appear from the accompanying drawings, the subjoined detailed description, and the appended claims.

In the drawings—

Figure 1 is a longitudinal, sectional view of a bottom hole plug, embodying my invention.

Figure 2 is a sectional view taken on line 2—2 of Figure 1.

Figure 3 is a longitudinal, sectional view of a modified type of plug, embodying my invention.

Figure 4 is a sectional view taken on line 4—4 of Figure 3.

Figure 5 is a longitudinal, sectional view of another modified form of heaving plug, embodying my invention.

Figure 6 is a sectional view taken on line 6—6 of Figure 5.

Figure 7 is a longitudinal, sectional view of still another modified form of bridging or heaving plug, embodying my invention.

It is common oil field practice to close in the lower end of the liner of an oil well by cutting segments from the lower end of the liner and then folding these segments inwardly to form a closure. The reason for this closing of the liner is to prevent the material of the oil-producing formation from pushing upwardly into the liner during the operation of the well.

It is also common oil field practice to attach a closed metal shoe to the lower end of the liner. From time to time, it is necessary to shut down an oil well in order that quantities of sand, and the like, may be removed from the liner. These materials are carried into the liner through the slots or openings by the flow of oil. To remove these materials, various types of clean-out bailers are lowered into the well on a cable, or other means, until the tool comes to rest on the material to be removed. The clean-out tool is then filled or loaded either by some mechanical means, or by raising and dropping the tool on the material. In any case, considerable weight is dropped on the material in the well while the cleanout tool is being filled. It frequently happens that due to a mistake in measurements or other misinformation, the operator will have cleaned out the liner to the bottom unknowingly and will continue to raise and drop the tool, thus subjecting the bottom of the liner or shoe to severe but unintended treatment, with the result that the liner or shoe will split or burst. When this has been done, sand or other material will be forced upwardly into the liner because of the flow of oil or gas, causing a great deal of difficulty.

Bridging and heaving plugs which are positioned in an oil well are also usual and well-known in the art, but it is the purpose of my invention to provide a plug, either a bottom hole, bridging, or heaving, with a means of registering the existing well bottom and to prevent the unintentional rupturing of the lower pipe extremity by contact with well tools. This means of registering the existing well bottom is accomplished by forming the plug of a frangible or recoverable material, which is easily distinguishable by the operator, and thereby quickly indicating to him that bottom has been reached.

Referring first to Figures 1 and 2, which is particularly a bottom hole plug, my invention consists of an elongated, cylindrical body formed of a frangible material, such as cement or the like, and which may be further distinguished by being colored with an insoluble coloring matter, or including unusual material, such as glass, the fragments of a bright metal, or the

like. The cylindrical body 1 is substantially the same diameter as the well casing, and to permit fluid in the well to by-pass the plug in its downward movement, I provide longitudinally extending grooves or slots 2, in the periphery of the plug body. The plug is lowered to bottom by the supporting means 3, which consists of a bolt 4, which is fastened in the body 1 of the plug, and extends upwardly a suitable distance. The bolt 4 may be threaded or otherwise secured in the body of the plug. A head 5 is provided on the upper end of the bolt 4. A sleeve 6 surrounds the bolt 4, and this sleeve includes a coupling 7, to which rods, a cable or the like are attached.

The lower end of the sleeve 6 is sharpened, as shown at 8, for the purpose of cutting into the frangible or cementitious material of the body around the bolt 4. This cutting action is accomplished by bearing downwardly with the suspending rods or cable until the bottom of the bolt 4 is reached, then the bolt will break loose and the plug is left in the hole resting on bottom. Since the plug is resting on the bottom of the liner or the shoe, no means is required to support or hold the plug in the well.

In Figures 3 and 4, I have disclosed a bridging or heaving plug, consisting of a substantially cylindrical body 9, which is preferably formed of a frangible, cementitious material, and preferably impregnated with an insoluble coloring pigment. The lower end of the body 9 is encased in a sleeve 10, preferably metallic. The sleeve 10 is formed with inwardly tapered seats 11, upon which a plurality of slips 12 rest. Upward movement of the slips 12 is limited by the shoulder 13. An outwardly tapered seating portion 14 is also provided on the sleeve 10, and slips 15 rest against this latter seat. A coil spring 16 bears against the bottom of the slips 15, and rests on the shoulder 13, thus urging the slips 15 upwardly on the seat 14. The upward movement of the slips 15 is limited by the following arrangement:

A bail 16 is attached to the plug by shear pins 17, substantially as shown in Figure 3. The lower end of this bail engages the slips 15, as shown in Figure 3, thus holding these slips downwardly and retracted until the plug is ready to be set. Plates 18 hold the pins 17 in the body of the plug until they are sheared, as will be further described. An eye 19 on the bail 16 enables a suitable lowering means to be attached to the bail, such as cable and the like. In running the plug into the well, the natural drag of the slips 12 against the casing will hold these slips in an upward retracted position. When the point has been reached where it is desired to set the plug, the cable which supports this plug is pulled upwardly and this sets the slips 12 into the casing. A continued upward pull will then shear the pins 17, and the bail 16 is pulled to the surface. The coil spring 16 now operates and pushes the slips 15 upwardly and outwardly to engage the casing. The slips 12 thus prevent upward movement of the plug, and the slips 15 prevent downward movement of the plug. It will be evident that the plug is thus fixedly held at any point in the casing against both upward or downward movement. An artificial or secondary bottom is thus provided for the well, this procedure transpiring where it is desired to abandon the lower portion of a well or to redirect the hole to another direction, or to produce from another formation.

In Figures 5 and 6, I have shown another modi-

fied type of heaving plug, which consists of an outer metallic sleeve 20. This sleeve is preferably closed at the bottom, as shown at 21. The sleeve is filled with a frangible material, preferably cementitious, and might be colored as previously described, this inner cylindrical body being shown at 22. A slip ring 23 may be integrally formed with the sleeve 21, or may be threadedly attached, as shown in Figure 5. The slip ring is provided with tapered seats 24, against which slips 25 rest. A shoulder 26 limits the upward movement of the slips 25. A bendable pin 27 is set in the slip ring 23 adjacent the upper end thereof, and this pin is rather loosely fit into the slip ring for purpose to be further stated. An eye 28 on the pin 27 enables a cable or the like to be attached thereto for the purpose of lowering the plug into the well. When the desired point in the well has been reached, an upward pull and upward movement of the plug will set the slips 25 into the casing, thus fastening the plug in position. Further upward pull on the lowering means will bend the pin 27 until it pulls out of the slip ring 23, and thereafter the cable or other lowering means can be recovered from the well.

In Figure 7, I have disclosed a structure somewhat similar to that disclosed in Figure 5, with the exception that suitable slips are provided to prevent both upward and downward movement of the plug. An outer cylindrical casing 29 encloses and retains the cementitious inner core 30. The slip ring 31 is provided with lower tapered seats 32, against which the slips 33 bear. The upper slips 34 bear against the outwardly tapering seats 35. A bendable pin 36 extends through the wall of the slip ring 31 and into the slips 34. An eye 37 on the pin 36 is attachable to a cable, or the like, when lowering the plug into the well. A coil spring 38 bears against the bottom of the slips 34, and urges these slips upwardly. To set the plug in the well, upward movement of the plug on its supporting cable will set the slips 33 into the casing, thus preventing further upward movement of the plug. The supporting cable is now strained upwardly until the pin 36 bends and is pulled out of the slips 34 and the slip ring 31. Since the slips 34 are released, the spring 38 will urge them upwardly and set them against the casing, thus holding the plug against downward movement. Since the cable is released from the plug, it can now be reeled to the surface.

Having described my invention, I claim:

1. A well plug consisting of a body of frangible material, a pin imbedded in the material and rising from the top thereof, lowering means engaging the pin, said lowering means being longitudinally movable on the pin and adapted and arranged to break the frangible material to release the pin from the body of said frangible material.

2. A well plug consisting of a body of frangible material, a pin imbedded in the material and rising from the top thereof, lowering means engaging the pin, said lowering means being longitudinally movable on the pin and adapted and arranged to break the frangible material to release the pin from the body of said frangible material, said frangible material being impregnated with a coloring matter.
